UNITED STATES PATENT OFFICE.

AUGUST MAZZI AND FRANK MARTINI, OF VINELAND, NEW JERSEY.

DEVICE FOR CALIBRATING TRANSPARENT TUBES.

1,394,423.

Specification of Letters Patent.

Patented Oct. 18, 1921.

Application filed July 1, 1920. Serial No. 393,370.

To all whom it may concern:

Be it known that we, AUGUST MAZZI, a citizen of the United States, and FRANK MARTINI, a subject of the King of Italy, 5 respectively, residing at Vineland, in the county of Cumberland and State of New Jersey, have invented certain new and useful Improvements in Devices for Calibrating Transparent Tubes; and we do declare the 10 following to be a full, clear, and exact description of the invention, such as will enable others skilled in the art to which it appertains to make and use the same.

This invention relates to devices for calibrating transparent tubes.

The main object of this invention is to provide an improved device whereby the gaging of burettes, pipettes and other transparent tubes can be effected with excessive 20 accuracy and despatch, by any person of ordinary ability, for enabling the operator to accurately mark the tube to indicate measuring divisions of co-equal cubical capacity.

25 Other objects and advantages will be pointed out or implied in the following details of description, in connection with the accompanying drawings, in which:

Figure 1 is a somewhat diagrammatic 30 view partly in vertical section, of a gaging apparatus constructed and arranged in accordance with our invention,

Fig. 2 is a side elevation of an improved windlass and its mounting and controlling 35 elements such as shown in end elevation in Fig. 1,

Fig. 3 is a top plan view of the device shown in Fig. 2,

Fig. 4 is a vertical sectional view along 40 the axis of the windlass,

Fig. 5 is a fragmental detail view of the device as seen from the right-hand of Fig. 2, parts being broken away and a portion of the ratchet-teeth being omitted,

45 Fig. 6 is an enlarged vertical sectional view of one of the windlass-bearings,

Fig. 7 is a fragmental detail view of a portion of the axle of the windlass,

Fig. 8 is an enlarged detail view illustrating the connection of two of the displacement members, and

Fig. 9 is a horizontal sectional view along the line 9—9 of Fig. 1.

Referring to these drawings in detail, in 55 which similar reference characters corre-

spond with similar parts throughout the several views, the invention consists in the construction and arrangement of parts which will now be described as follows:

Referring to Fig. 1, a transparent tube 60 T is shown in position to be calibrated, the lower end of this tube being in registration with and open communication with the upper end of a liquid container 1, this container being provided with an upwardly 65 facing tube-seat on which the lower end of the tube T is seated while being calibrated. This tube-seat consists of an inwardly extending endless flange or cushion which is formed integrally with an elastic tubular 70 element or sleeve 2, preferably of rubber; and the lower end of this tube or sleeve 2 embraces the upper end of the container 1 and the lower end of the tube T, thereby forming a water-tight connection between 75 the container and tube.

As a convenient, effective, exceedingly simple and comparatively cheap adjustable supporting means for the container 1 and tube T, we provide a supporting rod 3 which 80 preferably extends vertically from the floor to the ceiling of a room in which the device is to be operated. Spring clamps 4 are adjustably secured by means of set-screws, or other appropriate means, on the rod 3, and 85 these clamps may be of any appropriate form or construction for automatically adjusting themselves to embrace tubes of slightly varying diameters, and are quickly and easily removable from the rod 3 so as 90 to be replaced by others of greater or less capacity, or to be replaced by new ones in case of breakage or other defects.

Water is supplied to the container 1 from a supply tank or reservoir 5 which is positioned above the level of the tube or tubes to be calibrated, the water passing from the tank 5 through a pipe 6 and a valve 7 into the container 1. A valve 8 is provided for controlling the flow of water from the container 1, this valve being connected with an outlet pipe 9 which may discharge the water into a bucket (not shown), so that the water from the bucket can be poured into the tank 5 and used repeatedly, or else, water can be 95 supplied to the tank from a continual or constant source, and the waste water through the valve 8 and pipe 9 may be disposed of in any suitable way. By means of the valves 7 and 8, any desired water level may be ob- 100 105 110

tained within the container 1 or tube T. In other words, preparatory to the actual calibrating operation of a tube T, the water level should be half or near the lower end of the tube, according to where the calibrating of the tube is to begin. Therefore, water may be admitted through the valve 7 after a tube T has been placed in the position shown in Fig. 1, and if the water level is too high in the tube, upon closing the valve 7, the valve 8 may be opened slightly so as to lower the water level; or else the correct water level may be obtained in the container 1 or in its upward extension 2 before the tube T is seated and clamped in position.

The actual calibrating is effected by means of one or more displacement members on rods 10. There may be any number of these rods or members 10, according to the maximum number of graduations or measurements to be indicated on the tubes to be calibrated. As shown in Fig. 1, there is a series or chain of inter-connected spaced members 10, their connections being indicated at 11. These connections may each consist of a relatively narrow and thin strip or wire of any appropriate material and secured to the members 10 in any appropriate way. At 12 is indicated a supporting line or flexible element which is connected to the uppermost one of the members 10 and constitutes a means for lowering the chain of displacement members 10 into the tubes and containers 1 and for raising this chain of members 10 out of the tubes T.

As an appropriate means for actuating the line or cable 12, we provide an appropriate windlass 13 such as illustrated in Figs. 2 to 5 inclusive, or of other appropriate construction, and the line or cable 12 is wound thereon so as to move the unwound part longitudinally. The line or cable 12 extends over a pair of sheaves or wheels 14 which are journaled in opposite ends of a bearing member or bar 15 which is vertically adjustable by means of a screw 16 which is threaded in the middle portion of this bar 15 and has a swivel connection with a bracket 17 which depends from the ceiling 50 of the room and includes vertical guide bars 18 along which the bar 15 slides up and down while being adjusted, and a hand-wheel 19 is provided on the screw 16 for manipulating or rotating the latter. One 55 of the sheaves 14 is vertically aligned with the upwardly facing seat for the tubes T, and when one of these tubes is in the gaging position, this sheave 14 holds the chain of displacement members approximately in alignment with the tube T. However, this 60 sheave 14 also serves as a stop for limiting the upward movement of the chain of displacement members, and when the uppermost one of these members is drawn tightly 65 against the sheave 14, this has a tendency

to throw the displacement members out of vertical alinement with the tube T. Therefore, we provide a ringlike guide 20 through which the series of displacement members move up and down, and this guide member 70 accurately guides the displacement members into the upper end of the tube T in the position to be calibrated. The guide 20 is preferably adjustable vertically on the supporting rod or upright 3 so that it can be 75 placed in the most effective position with relation to tubes of different lengths. The displacement members 10 may be of any appropriate dimensions or shapes, but each of them must be of a predetermined size or 80 mass; that is, each member 10 must be of a predetermined cubic displacement, according to the measurement it is intended to indicate on the transparent tube T. Therefore, each member 10 will indicate a predetermined measurement on the tube T regardless of whether the tube be of a certain diameter or of a slightly larger or smaller diameter.

The purpose of the device illustrated in 90 Figs. 2 to 7 inclusive, is to effect a step by step movement of the series of displacement members 10 into the container 1, that is to move one of the members 10 into the liquid, then a second, then a third, a fourth, etc. 95 In order to accomplish this step by step movement, the windlass is provided with two ratchet wheels 21 and 22, these ratchet wheels being either formed integrally with the drum of the windlass 13 or secured thereto in 100 any appropriate way, one way being illustrated in Fig. 4 where pins 23 extend through the winding drum and through the inwardly extending bosses of the wheels 21 and 22. These two pins also extend through the axle 105 24 which carries a handle or crank 25 by means of which the windlass can be rotated by the hand of the operator. Outwardly extending bosses surround the shaft or axle 24 and combine with the latter to form journals which are rotatably and longitudinally seated in bearings 26 and 27 of a supporting frame which is provided with upward extensions or bearings 28 which carry pawls 29 and 30. The extensions or uprights 28 also 110 carry bifurcated guides 31 and 32 for preventing horizontal movement of the pawls 29 and 30, while permitting them to swing about their respective pivots. Each of these pawls is provided with a spring 33 which 115 yieldingly holds it in a substantially horizontal position. As shown in Fig. 5, the ratchet-teeth of the wheel 22 are outwardly inclined in the circumferential direction opposite to that in which the teeth of the wheel 120 21 are inclined. In other words, as viewed in Fig. 5, the teeth of the wheel 21 point in the clockwise direction, and the teeth of the wheel 22 point in the contra-clockwise direction. The pawl 29 is adapted to en- 125 130

gage with or fit between the teeth of the wheel 21, and the pawl 30 is adapted to fit between the teeth of the wheel 22, the lower working edges of these pawls being in-

- 5 clined according to the inclination of the teeth with which they engage, so that each pawl permits the windlass to be turned in one direction and holds it against turning in the opposite direction; for instance, when
 10 the pawl 29 is engaged with the wheel 21, as shown in Fig. 1, the windlass can rotate only in the contra-clockwise direction. However, by moving the windlass axially so as to release the wheel 21 from its pawl
 15 and engage the wheel 22 with its pawl, as shown in Figs. 4 and 5, the windlass can be rotated only in the clockwise direction.

The windlass can be alternately and yieldingly secured in the positions shown in Figs. 20 2 and 4 by any appropriate retaining means, but a very simple and effective means is shown in Figs. 6 and 7, in which the shaft or axle 27 is provided with a diametral bore or plunger-seat in which a pair of plungers 25 or detents 34 are seated for axial movement. A spring 35 is compressed between the plungers 34 and constantly tends to press these plungers outward. The bearing 26 is provided with two peripheral grooves 36 in
 30 which the pair of plungers 34 extend alternately. That is, when the windlass is in the position shown in Fig. 2, the plungers 34 ride or slide in the outer or right-hand groove 36, and when the parts are in the
 35 position shown in Fig. 4, these plungers or detents ride in the inner or left-hand groove 36. However, because of the cone-shaped or outwardly tapering ends of the plungers 34, and the corresponding sides of the grooves
 40 36, these plungers are pressed inward when a sufficient axial pressure is applied to the crank 25.

From the foregoing description, it will be seen that when the cable 12 is wound 45 upon the windlass 13, as shown in Fig. 2, it will be necessary to move the windlass axially to the position shown in Fig. 4 in order that the cable 12 may be unwound for lowering the displacement members 10; but
 50 on the other hand, if the cable 12 is wound oppositely on the drum of the windlass, it could be unwound by turning the windlass in the contra-clockwise direction while in the position shown in Fig. 2. It should be
 55 understood that one end of the cable 12 is secured to the windlass by any appropriate means, and that this windlass is provided with helical guides or a guiding rib or thread
 60 37 and a consequent helical groove 38 in which the cable 12 is wound to prevent the line or cable 12 from crossing itself, thereby insuring an equal movement of the displacement members for each revolution of the windlass. However, it is the purpose of the
 65 equally spaced ratchet teeth of the wheels

21 and 22 to effect equal movements of the displacement members by a series of step by step partial revolutions of the windlass, and this is effected in the following manner:

Assume that the pitch distance, that is, the 70 distance from the lower end of one member 10 to the lower end of the next one above, is one inch, and that by rotating the windlass through a circumferential distance of four of the ratchet teeth, exactly one inch of 75 the line 12 is unwound from the windlass. This moves the chain of members 10 downward one inch each time the windlass is rotated a distance of four of its ratchet teeth. Now, assuming the device to be in the position shown in Fig. 4, the ratchet will click 80 four times, thereby notifying the operator that the displacement members have moved the proper distance, that is, its pitch distance, one inch. If the displacement member was at the proper starting position, this downward movement displaces a quantity of water from the tank or container 1 equal to the size of the displacement member, and this displaced water rises into the tube T. 85 The operator now marks the tube T at the level of the water therein, and then manipulates the crank 25 for moving the windlass an additional four teeth of its ratchet wheels, thereby effecting another step of the 90 series of displacement members downward into the container 1 and tube T, thus indicating another measurement to be marked at the water level in the tube T. When the operator has marked the tube T at this water 95 level, the operation is repeated until the water level has approached the top of the tube T, whereupon the rotation of the windlass is reversed and the series or chain of displacement members thereby raised out of 100 the tube T. In cases where the members 10 are relatively small and of light weight, the pawl 30 may be sufficient to sustain the weight of these members, especially after a number of them have become submerged, 105 and the buoyancy of the water assists in sustaining their weight. However, in cases where the pressure and friction of the pawl 30 is insufficient to hold the windlass against excessive forward movement, the operator 110 pulls the handle 25 in the direction for moving the windlass rightward, thereby bringing the teeth of the wheel 21 into engagement with the pawl 29, and this pawl acts as a positive stop for preventing excessive 115 movement of the windlass.

Although the links, bonds or connecting elements 11 are so small that the quantity of water displaced thereby is substantially negligible, the device is rendered exceedingly 120 accurate by means of the adjusting screw 16 and its adjuncts, because an infinite number of adjustments can be obtained by this means. In this connection, it is to be understood that when the diameter of the tube T 125

varies, the water level will vary with relation to the displacement members 10; whereas for perfectly accurate gaging, the water level should always register either with the 5 upper end, the lower end or at a predetermined distance from the upper and lower ends of the tubes, that is, at a predetermined point on each link or connector 11. In case an unwinding strip of the windlass does not 10 position the displacement members at one of these predetermined points with relation to the water level, the screw 16 is manipulated by the operator to raise or lower the displacement members, until the water level 15 registers with this predetermined point, between the ends of the displacement members. Moreover for the sake of saving time, it is always desirable to stop the lowermost displacement member at a slight distance above 20 the end of the tube to be gaged. Therefore, when short tubes are to be calibrated, the screw 16 is manipulated for lowering the displacement members; and on the other hand, when long tubes are to be calibrated, the displacement members are raised by means of 25 the screw 16; that is the wheel 14 which acts as a stop is raised to such position that the uppermost member 10 abuts against this wheel when the lowermost one is only 30 slightly above the tube being calibrated.

When the calibrating of one tube has been completed, it is slid upward through the clamps until its lower end is above the level of the flexible sleeve 2, and it is then moved laterally out of engagement with the clamps 35 4; whereupon another tube is passed laterally into the clamps 4 and then moved downward onto the seat of the sleeve 2.

It is not intended to limit this invention 40 to the exact details of construction and arrangement as described, but changes may be made within the scope of the inventive ideas as implied and claimed.

What is claimed is:

45 1. In a device for calibrating open ended transparent tubes, a liquid container having an upwardly facing tube-seat provided with an opening adapted to communicate with the interior of the tube to be calibrated through one of the open ends of the tube, means to interchangeably secure tubes on said seat and prevent leakage between said seat and a tube, a chain of duplicate displacement members each for displacing a predetermined cubic quantity of liquid in the tube and a suspending element to lower said displacement members through the tube into 50 said liquid container.

60 2. In a device for calibrating open ended transparent tubes, a liquid container having an upwardly facing tube-seat provided with an opening adapted to communicate with the interior of the tube to be calibrated through one of the open ends of the tube, means to 65 interchangeably secure the tubes on said seat

and to prevent leakage between said seat and each tube, a series of interconnected spaced members each for displacing a predetermined cubic quantity of liquid in the tube and a suspending element to lower said displacement members through each tube into 70 said liquid container.

3. The structure defined by claim 1, and separate means for causing liquid to rise in each tube from said liquid container and to 75 recede into the latter.

4. The structure defined by claim 1, said liquid container being provided with a valved inlet and a valved outlet, a reservoir 80 at a level above the level of said seat, and a conduit in open communication with said inlet, whereby the liquid can be caused to rise from said container into each tube on said seat and to recede from each tube into 85 said container, substantially as specified.

5. The structure defined by claim 1, a vertical supporting and guiding member, and a tube-securing member mounted for vertical adjustment on said supporting and guiding member so as to be properly engaged 90 with tubes of different lengths on said tube-seat for securing these tubes in the gaging position.

6. The structure defined by claim 1, and means to support and vertically adjust said 95 suspending means.

7. The structure defined by claim 1, and a screw-actuated adjusting device capable of effecting an infinite number of accurate vertical adjustments of said suspending element, for the purpose specified.

8. The structure defined by claim 1, means including a sheave for supporting said suspending element and limiting the upward movement of said displacement member, and 105 means to effect an infinite number of vertical adjustments of said sheave wheel, for the purpose specified.

9. The structure defined by claim 1, and means to effect a series of predetermined 110 vertical adjustments of said suspending means.

10. The structure defined by claim 1, a windlass connected to said suspending element for effecting vertical adjustments of the latter, a ratchet wheel connected to and rotatable with said windlass, and a pawl for co-acting with said ratchet wheel to control said windlass, said ratchet wheel being axially shiftable into and out of engagement 115 with said pawl.

11. The structure defined by claim 1, said tube-seat consisting of an elastic tubular body formed with an endless inwardly projecting cushioning flange which overlies the material about the opening of said liquid container, the part below said flange embracing said container, the part above said flange being adapted to embrace the tubes to be gaged.

12. The structure defined by claim 1, a vertically disposed supporting rod, means carried by said rod to hold and vertically adjust said liquid container, means on said 5 rod to hold and vertically adjust the tubes to be gaged, and a guide for said displacement member mounted for vertical adjust-
ment on said rod, said guide being vertically aligned with said opening of the liquid container, for the purpose specified. 10
In testimony whereof we have hereunto set our hands.

AUGUST MAZZI.
FRANK MARTINI.
